(57) **CLAIM**

The ornamental design for a cabin divider, as shown and described.

DESCRIPTION

FIG. 1 is a perspective view of the cabin divider showing our new design;

FIG. 2 is a front view of the cabin divider of FIG. 1;

FIG. 3 is a rear view of the cabin divider of FIG. 1; and,

FIG. 4 is a left view of the cabin divider of FIG. 1.

In FIGS. 1-4, broken lines showing the interior and seats of a cabin depict environmental structure which forms no part of the claimed design. The broken lines in FIG. 3 show portions of the cabin divider which form no part of the claimed design.

1 Claim, 4 Drawing Sheets

FIG. 1

FIG. 2
